UNITED STATES PATENT OFFICE.

JOSEPH ARTHUR BEAUDOIN, OF MONTREAL, QUEBEC, CANADA.

SWITCH-ACTUATING MECHANISM.

1,405,179.

Specification of Letters Patent. Patented Jan. 31, 1922.

Application filed August 2, 1921. Serial No. 489,284.

To all whom it may concern:

Be it known that I, JOSEPH ARTHUR BEAUDOIN, a subject of the King of Great Britain, residing at Montreal, in the Province of Quebec, Canada, have invented certain new and useful Improvements in Switch - Actuating Mechanism; and I do hereby declare that the following is a full, clear, and exact description of the invention, such as will enable others skilled in the art to which it appertains to make and use the same.

The present invention relates to new and useful improvements in switch actuated mechanism.

The primary object of the invention is the provision of a switch actuating mechanism for street railways and the like, so designed that the switch will be automatically turned to the desired position upon the approach of a car thereto.

Another object of the invention is the provision of means for either opening or closing the switch upon the approach of a car thereto from either direction.

Still another object of the invention is the provision of electrical means for actuating the switch in the desired position upon the approach of a car thereto.

A still further object of the invention is the provision of a switch actuating mechanism controlled by a series of magnets, which derive their power from trolley wires, so arranged that the switch may be thrown to the desired position from any distant point, dependent upon the position of an operating handle actuated by the motorman, so that the switch will be properly turned upon the approach of a car.

A still further object of the invention is the provision of a switch actuating mechanism, such as above referred to, which will be comparatively simple and inexpensive to manufacture, reliable and efficient in use and readily operated.

With the above and other objects in view, the present invention resides in the novel features of construction, formation, combination and arrangement of parts to be hereinafter more fully described, claimed and illustrated in the accompanying drawings, forming a part of the present application, and in which;

Figure 1 is a side view showing the invention applied to the usual street railway car;

Figure 2 is a plan view showing the switch;

Figure 3 is a side view of a portion of the trolley;

Figure 4 is an end view of the trolley;

Figure 5 is a plan view of a portion thereof;

Figure 6 is a diagrammatic view illustrating the complete wiring of the actuating magnets;

Figure 7 is a similar view showing the wiring of one set of magnets; and,

Figure 8 is a similar view showing the wiring of the opposite set of magnets.

Figure 9 is a diagrammatical view illustrating the wiring of the magnets 15 and 16.

Referring now to the accompanying drawings by corresponding characters of reference throughout the several views; the numeral 10 designates in general the tracks of a street railway line, in which the switch points are shown at 11. Each of the points 11 is pivoted to a disk 12, the rotation of which serves to open or close the switch as occasion might necessitate.

A pair of diametrically opposite arms 13 extend from each of the disks 12 and are provided with contact members 14 which are controlled by the magnets 15 and 16 arranged in alternate pairs as clearly shown in Figures 6, 7 and 8 of the drawing.

A street railway car is shown at 17 and may be of any well known or desired construction. This car 17 is equipped with a trolley pole 18 provided with the usual trolley wheel 19 and additional trolley wheels 20 and 21 placed upon the opposite sides of the said wheel 19. The trolley wheel 19 is designed to engage the usual trolley wire 22 for supplying current to the car, and the supplementary or additional trolley wheels 20 and 21 which are spaced upon the opposite sides thereof are designed to engage each of the auxiliary trolley wires 23 and 23^a respectively. One end of the wire 23 is connected by the conductor 24 to the magnets 15 located for cooperation with the disks 12, as is clearly shown in Figure 6, while one end of the trolley wire 23^a is connected by the conductor 25 to the magnets 16. The op-

posite ends of the magnets 15 and 16 are both grounded to the track by the wires 26.

From the trolley wheels 20 and 21 lead the wires 30^a and 30^b which lead through the car as indicated in Figure 9. The ends of said wires are each connected to one of the switch contact points 29^a and 29^b. A switch 29 is located in proximity to the motorman to cooperate with said contacts 29^a and 29^b. A switch lever 29^c is connected to the main line by the wire 30 and current is supplied from the trolley wheel 19.

From this construction it is obvious that if the motorman wants to turn his car to the left, he will throw the switch 29 in contact with the contact point 29^a, and thus the current will be supplied to the magnets 15; and if so desired solenoids can be used instead of the ordinary electric magnet shown in the accompanying drawings.

Obviously when current is supplied to the magnets 15 by the proper conductors these magnets will be energized to attract the arms 13 and the disks 12 will be rotated in the direction shown in Figure 7 and when the magnets 16 are energized the disks will be drawn to the position shown in Figure 8 thus moving the switch points to their opposite position. The circuits in which the wires 23 are included lead through the car and either of the circuits may be broken by means of the switch 29 which may be actuated by the motorman so as to throw the switch points to the desired direction upon the approach of his car.

It will be noted that the supplemental trolley wires 23 and 23^a are only used as the car approaches the switch and otherwise only the trolley wire 22 is used in the customary manner.

From the foregoing description taken in connection with the accompanying drawings it will be manifest that a switch actuating mechanism for street railway cars is provided which will fulfil all of the necessary requirements of such a device, and it should be understood in this connection, that various minor changes in the specific details of construction can be resorted to within the scope of the appended claims, without departing from the spirit or sacrificing any of the advantages of the invention.

Having thus fully described the invention what I claim as new and desire to secure by Letters Patent is:

1. The herein described apparatus comprising in combination with movable switch points, rotatable disks pivotally connected to the switch points, for throwing the switch

points in opposite directions, and magnets for controlling the movements of said disks substantially as and for the purposes set forth.

2. The herein described switch operating mechanism including the combination of movable switch points, disk pivoted to said switch points, for moving the latter in opposite direction upon the rotation of said disks, magnets controlling the rotation of said disks, means for supplying current to the magnets and means for changing the current to opposite sets of magnets and rotating the disks in opposite direction.

3. The herein described switch actuating mechanism, including the combination with switch points, a disk pivotally connected to each of the switch points, the disks being rotatably mounted, arms extending from said disks, magnets arranged in pairs for attracting the arms and rotating the disks in opposite direction, means for supplying current to the magnets, and means for reversing the current to the opposite magnets, substantially as and for the purposes set forth.

4. The herein described switch actuating mechanism, including the combination with a street railway car, and a switch including switch points, of a trolley including additional wheels mounted upon the street railway car, supplemental trolley wires engaging said additional trolley wheels, magnets connected to said supplemental trolley wires for receiving current therefrom, disks operatively connected to the switch points, arms extending from the disks and controlled by said magnets, and a controlling mechanism mounted within the car for controlling the current to opposite pairs of magnets, for rotating the disks in opposite direction and properly moving the switch points.

5. The combination in an apparatus such as described with a switch and a street railway car, said switch including movable switch points, disks pivotally connected to said switch points, arms extending from the disks, magnets arranged upon opposite sides of the arms for actuating said arms, a trolley for supplying current to the magnets, and means for controlling the current to opposite sets of magnets for attracting the arms in opposite directions and throwing the switch points in opposite directions, substantially as and for the purposes set forth.

In witness whereof I have hereunto set my hand.

JOSEPH ARTHUR BEAUDOIN.
